D. BLANCHARD.
Turn-Bridge and Turn-Table.

No. 222,375.

Patented Dec. 9, 1879.

UNITED STATES PATENT OFFICE.

DUDLEY BLANCHARD, OF BROOKLYN, NEW YORK, ASSIGNOR TO HIMSELF
AND JOHN H. O'ROURKE, OF SAME PLACE.

IMPROVEMENT IN TURN-BRIDGES AND TURN-TABLES.

Specification forming part of Letters Patent No. 222,375, dated December 9, 1879; application filed September 11, 1879.

To all whom it may concern:

Be it known that I, DUDLEY BLANCHARD, of Brooklyn, Kings county, in the State of New York, have invented certain new and useful Improvements relating to Turn-Bridges and Turn-Tables, of which the following is a specification.

The bridge is mounted on a series of conical rollers traveling on a circular track concentric with the pivot, and is provided, in accordance with the usual practice, with additional wheels mounted farther out from the center. These are expected to bear only when the bridge is unequally loaded or not exactly balanced.

I have devised important improvements in the details. The central rings or tracks on which the rollers turn are adjustable in height, so that the bridge may be raised and lowered to secure the best position or to compensate for settling. My adjusting means allow one side of the bridge to be raised without the other. The rollers are mounted on rigid pins projecting from an internal frame or spider, and provided with a loose sectional connection forming a ring outside of the rollers. This attains important ends described farther on. The wheels outside are mounted in pairs tilting on a center, and each pair of wheels is adjustable in height to allow its being held in the desired condition, not bearing any of the weight while the bridge is properly balanced, but ready to bear immediately if the bridge is loaded unequally.

The accompanying drawings form a part of this specification, and represent what I consider the best means of carrying out the invention.

Figure 1 is a plan view. Fig. 2 is an end view. The remaining figures represent details detached. Fig. 3 represents the central pivot and base of same in elevation. Figs. 4 and 6 are plan views of the upper and lower ways or plates, and Fig. 5 a central vertical section of either. Fig. 7 is a plan view of the spider and connections, and Fig. 8 is a central vertical section of the same on the line S S. Fig. 9 represents the plate or strap connecting the axles of every two rollers in side and top view. Fig. 10 is a side view of one of the outer trucks, and Fig. 11 is a view of the same at right angles to Fig. 10.

Similar letters of reference indicate corresponding parts in all the figures.

A is a foundation of masonry or other substantial material. B is a stout bed-casting resting thereon. It supports a stout accurately-turned central pivot, M, to which the several members above are adapted to fit closely and be truly centered thereby. The casting B is also formed with holes to receive a series of stout jack-screws, C, which are tapped through nuts c, resting on the casting B. The tops of the screws C are slightly rounded, and the entire series forms a level surface to support the lower ring or way D.

E, &c., are conical rollers of steel or other suitable material mounted on rigid pins f projecting radially from a loose revolving casting or spider, F. G is an upper way resting on the rollers E, and bearing the weight of the bridge. The bridge may be of any ordinary or suitable construction. I will designate it by the single letter H. A strongly-secured casting, h, is formed with a truly-bored hole, which receives the pin M and holds the whole centrally.

I is a circular track, concentric to the pin M, and strongly supported. J J are wheels, adapted to follow each other on the track I. They are mounted in pairs in tilting trucks K, which oscillate on horizontal shafts or centers k, which are held by straps l in bearings in stout castings L. The latter are secured at the proper points to the bridge H by two sets of bolts or threaded connections, P Q.

The screws P are tapped through the casting L, and bear against a plate on the under side of the bridge H. These take the load when in the use of the bridge it bears heavily on the truck. The screws Q are inserted loosely through the casting L and tapped into the bridge.

In turning the bridge around, the trucks K tilt, as required, to accommodate any inequalities in the track I, and are adjusted up and down by the bolts P Q, so that their wheels J run close to or slightly touch the track I, but without supporting the bridge thereon, except when one end or part of the bridge is heavily loaded. Then that part being deflected downward by the load causes the corresponding

truck K to perform its function of aiding to support the load.

The distribution of the load by the tilting trucks K is important to compensate for inequalities in the track as well when the bridge is stationary as when it is being turned.

The adjustment by the bolts P Q is important to carry the several trucks accurately at the proper elevation.

The screws C form a means for adjusting the central work, and consequently the entire bridge, up and down, as required, and also of raising one end or one side without the other.

I esteem it important that the castings D G be of moderate size, so that they can be each formed in a single casting, and accurately turned in large lathes; but I prefer for bridges, or turn-tables carrying great loads, to make them of as large diameter as is convenient.

The number and size of the screws C may vary with the load.

The entire bridge may be raised by applying a long fork-wrench to the square part near the top of each screw, and turning each a little. If it be required to raise one side more than the other, the turning may be correspondingly manipulated.

A difficulty has been found in adjusting the rollers in this class of bridges. The conical form of the rollers and of their bearings upon the ways D G allows the bearing-strain on each to be adjusted by setting it inward or outward on its radial pin or axle f. There is a tendency in each to crowd outward. I resist this by a strong nut, F', and jam-nut F². These may be adjusted outward and inward, and caused to correspondingly adjust the roller; but the strong pressure of the roller against the nut induces a tendency to turn, which it is important to resist by an interposed plate which cannot turn, but which will at the same time offer no obstacle to the adjusting of the rollers outward and inward. I attain this by plates R, which are loosely coupled or spliced together by flanges r, aided by screw-bolts, (not shown,) if such shall be found expedient. The flanges r hold the plates R stiffly, so as to form a proper circular series, a practically-continuous but yielding strap, and thus relieve the nuts from being turned, while they also allow an end motion of each plate relatively to its neighbor, which is made available when the nuts are adjusted outward or inward. A continuous hoop could not allow the same adjusting action.

Modifications may be made without sacrificing the advantages of the invention. I can introduce screw-bolts or other means by greatly tightening the junction of the several plates R when their correct position has been attained. This will allow the plates R to somewhat brace the outer ends of the pins or axles f.

Wedges, with proper means for holding them accurately in position, may be used with success instead of screws in one or both places.

The central pin, M, may be cast in one with the

bed-casting B, or it may be forged of wrought-iron or steel and inserted in the mold so as to be united with the casting in the act of producing the latter, or it may be keyed in a hole formed in the casting.

It will be understood that in supporting large bridges both the sets of rollers or wheels E and J will traverse on the central pier.

There may be other ordinary bearing-rolls to take the extreme ends of the bridge and relieve the friction thereof when the bridge is nearly in position.

There may be anti-friction rolls between the spider F and the central pin M. The latter may be made of uniform diameter throughout, or made with one or more offsets, so that the portion at the top which enters the bridge H shall be considerably smaller than the part below. It may be hollow.

Any ordinary or suitable means may be availed of to induce the turning motion of the bridge.

I am aware that adjusting jack-screws have before been interposed between the bridge and the upper roller bearing-plate, and such arrangement of parts is not sought to be broadly covered in this application.

It is better to place the screws C under than over the ways D G, because it is easier to form sufficient depth of metal to hold them in the stationary than in the revolving part. There is no objection to making the screws and their holding-ground as massive as any exigency shall ever require.

I claim as my invention—

1. The circular series of adjusting-screws C, tapped into the stationary casting B, or into nuts c, resting thereon, as shown, in combination with the way D, rollers E, and way G, supporting the bridge H, as herein specified.

2. The plates or sectional strap R r, in combination with the rollers E, spider F f, and nuts F', adapted for use in connection with a bridge or turn-table, H, as herein specified.

3. The turning bridge or table H, central pin M, inner series or anti-friction bearing means, D E G, outer series of bearing means, I J, and tilting trucks K, free to rock on the centers k, all combined and arranged for joint operation, as and for the purposes herein specified.

4. In a turn-bridge or turn-table having a central pivot, M, and approximately central bearing-rolls, E, the outer rolls or wheels, I, mounted in a suitable truck frame, in combination with each other and with adjusting-screws P Q, for adjusting each set of the latter, as and for the purposes herein specified.

In testimony whereof I have hereunto set my hand this 9th day of September, 1879, in the presence of two subscribing witnesses.

DUDLEY BLANCHARD.
